UNITED STATES PATENT OFFICE.

THEOD. J. STEFFE, OF LANCASTER, PENNSYLVANIA.

IMPROVEMENT IN HORSE-RAKES.

Specification forming part of Letters Patent No. 25,535, dated September 20, 1859.

To all whom it may concern:

Be it known that I, THEODORE J. STEFFE, of the city of Lancaster, in the county of Lancaster and State of Pennsylvania, have invented a new and useful Improvement on Horse-Rakes, by which the several devices used all operate on the axle of the machine as their common center; and I do hereby declare that the following is a full, clear, and exact description of the construction and operation of the same, reference being had to the annexed drawings, making a part of this specification, in which—

Figure 1 is a perspective view of the several parts in place on the axle; Fig. 2 the round iron axle over or around which those devices are put. Fig. 3 shows the lifters *b* and lever *G* connected by the rod *B*. Fig. 4 shows the cleaners *c* connected in like manner by the rod *C* and attachment of its brace *K L*. Fig. 5 illustrates the operation of the lever *G* (centrally placed) on the brace *K L*, lifters *b*, and cleaners *c*. Fig. 6 shows one of the oval-eyed tooth-heads *E*, with a tooth, *D*, inserted and held by the key *N*, which has a hole, through which one end of a spiral spring is passed (*F*) from the rod *B* under each tooth. Fig. 7 shows the cleaner-brace *K L*, hinged at *I I*, with its slot *o* and slide *M*.

The projecting end *H* of the lever *G* is arrested by the slide *M* when brought over the slot *o*, and thereby draws the cleaners *c* downward as the teeth rise upward, and effectually removes all that might lodge upon them. When the teeth are wanted up, and the cleaners remain in place, (by the action of the springs *X* to the seat,) the slide *M* is brought forward, when the end *H* of the lever passes through the slot *o*, and the teeth are kept up by a pin through

the bar *Q* over the lever or its equivalent. The foot-board, seat, &c., are attached to the shafts, which surround the axle, in like manner as do the lifters, teeth-heads, lever, and cleaners, by their openings *A*. The lifters *b*, lever *G*, and the cleaners *c* have holes, through which their respective connecting-rods *B C* are passed. These rods have a head on one end, and the other end is provided with a burr and screw-thread. By this arrangement any injured piece can be readily replaced at a great saving of time and expense, as the entire rake can be taken apart and put together again in twenty minutes, besides adapting this rake admirably for transportation, storage, &c., as its separate pieces occupy but a small space when packed away, and in every other respect fully equal to any other device for operating in the field.

I am aware that, separately considered, it may seem to offer nothing new or novel; but, taken collectively, it is the opinion of all who have examined it to be both novel and useful. I do not claim any of its parts, therefore, separately considered.

What I claim as my invention, and desire to secure by Letters Patent, is—

1. The arrangement and combination of the teeth-heads *E*, key *N*, spiral-spring attachment *F*, lifters *b* *B*, lever *G H*, cleaners *c* *C*, when these several parts have their center of motion on the axle of the machine.

2. In combination with the above, the foot-brace *K L*, hinged at *I I*, slide *M*, and slot *o*, substantially as and for the purpose herein specified.

THEODORE J. STEFFE.
